UNITED STATES PATENT OFFICE.

MOUBRAY GORE FARQUHAR AND ARTHUR HENRY HILL, OF BIRMINGHAM, ENGLAND.

STAND OR SUPPORT FOR FIREARMS.

1,355,660.

Specification of Letters Patent.

Patented Oct. 12, 1920.

Original application filed April 15, 1919, Serial No. 290,267. Divided and this application filed September 26, 1919. Serial No. 326,631.

To all whom it may concern:

Be it known that we, MOUBRAY GORE FARQUHAR and ARTHUR HENRY HILL, subjects of the King of Great Britain, residing 5 at Birmingham, England, have invented certain new and useful Improvements in Stands or Supports for Firearms, of which the following is a specification.

Our invention consists of the improvements 10 hereinafter described in stands or supports for firearms the said improvements having for their principal objects to facilitate the carrying of the stand or support and to render the detachment of the same 15 from the fire arm when the latter is to be moved from place to place unnecessary.

The improved stand or support constituting our invention comprises a pair of struts or legs so attached to the fire arm that 20 when not required for use they may be folded into a position approximately parallel with each other and close to the underside of the fire arm in which position they are retained by a spring snap or like fastening, 25 the said struts or legs being so pivoted that when the fastening is released the struts or legs automatically take their depending and outwardly spread or diverging positions for use. The part carrying the struts or legs is 30 preferably made capable of adjustment longitudinally relative to the fire arm.

We will further describe our invention in connection with the accompanying drawing.

Figure 1 represents in elevation a portion 35 of a fire arm of the kind described, represented and claimed in the specification of our pending U. S. patent application Serial No. 290,267 filed April 15th 1919 of which the present application is a division, with 40 the new or improved stand or support applied thereto, the said stand being in its folded or out of use position.

Fig. 2 is a plan of the same with the legs or struts of the same (portions of which legs 45 or struts are broken away) in their depending or turned down position for use.

Fig. 3 is an end view of the fire arm and stand or support showing the legs or struts of the latter in position for use.

50 The same letters of reference indicate the same parts in the several figures of the drawing.

a, a are the inclined legs or struts of the stand or support and *b, b* are the pivots or 55 trunnions on the underside of the fire arm

on which pivots the adjacent ends of the legs or struts *a, a* are mounted. The pivots or trunnions *b, b* are so inclined relatively to the part on the underside of the fire arm by which they are carried that when the 60 said legs or struts *a, a* are turned thereon from the folded or out of action position represented in Fig. 1 into their depending position for use indicated in dotted lines in Fig. 1 and represented in full lines in Figs. 65 2 and 3 they automatically assume the outwardly inclined or spread out position best seen in Fig. 3.

To provide for the longitudinal adjustment of the stand or support relative to the 70 fire arm we arrange on the underside of the fire arm a girder-like or T section bar *c* the ends of which bar *c* are attached to the block *d* constituting the seat for the rear end of the tube or casing *e* of the spring actuating 75 mechanism of the fire arm and the fore end cap or seat *f* for the said tube respectively.

The pivots or trunnions *b, b* are carried by the block *g* the upper side or face of which is shaped to fit and slide on the 80 girder-like or T shaped bar *c*.

The legs or struts *a, a* when folded or turned into the out of use position lie side by side or parallel with one another and approximately close together against the underside of the girder-like bar *c* in which position they are retained by the engagement therewith of catches or a spring snap fastening such as is illustrated in the drawing and which we have found to answer well in 90 practice which consists of a bell crank lever pivoted at *i* one arm of which lever consists of a pair of hook-like parts *h¹, h¹* which when the legs or struts *a, a* are raised or turned into their out of use position automatically snap into engagement with holes 95 *a¹* in the splayed or disk-like feet of the legs or struts *a* the other arm of the lever indicated as *h*. The said hook-like parts of the lever are held in their engaging position 100 by the action on the arm *h* of the lever of the spring *k*.

When it is desired to release the legs or struts *a, a* it is only necessary to press the arm *h* of the snap fastening against the action of the spring *k* thereby removing the hooks *h¹* from the holes *a¹*, the liberated legs falling by their own weight and automatically taking their outwardly inclined or acting position as hereinbefore described. 110

We wish it to be understood that we do not limit ourselves to the employment of the rigid bar *c* as the part *g* thereon may be modified in construction so as to enable it to be fixed to other parts of the fire arm.

5 We claim:—

1. A stand or support for fire arms comprising in combination a bar adapted to be mounted on the underside of a fire arm, a head portion slidably mounted on said bar, a pair of strut members pivoted on inclined pins projecting from opposite sides of said head portion, said strut members being formed with flanged portions adjacent their free ends, and a catch member associated with the underside of said firearm and adapted to engage the flanges to retain the struts in inoperative position.
- 10 2. A stand or support for firearms comprising in combination a bar adapted to be mounted on the under side of a firearm, a head portion slidably mounted on said bar, a pair of strut members pivoted on inclined pins projecting from opposite sides of said head portion, said strut members being formed with flanged portions adjacent their free ends, said flanges having apertures

therein, and a catch member associated with the under side of said firearm and adapted to engage the apertured flanges to retain 30 the struts in inoperative position.

3. A stand or support for fire arms comprising in combination a bar of T section adapted to be fixed to the underside of a fire arm, a slide shaped to engage with and 35 work on the T section bar and a pair of legs pivoted to said slide by pins so inclined to the slide that the legs when folded up fit snugly and parallel under the fire arm and when allowed to turn on the screws or pivots 40 automatically take their outwardly inclined or operative position and means associated with the underside of the fire arm to releasably engage said legs in their inoperative position.

4. In a stand or support for fire arms having a barrel, a cylinder for housing the counter-recoil mechanism and spaced blocks for supporting said cylinder from the barrel, a guide bar mounted in said blocks, a 50 slide engaging said guide bar and a pair of legs pivotally supported on said slide.

MOUBRAY GORE FARQUHAR.
ARTHUR HENRY HILL.
